US00D854438S

(12) **United States Design Patent** (10) **Patent No.:** **US D854,438 S**
Selevan et al. (45) **Date of Patent:** **** Jul. 23, 2019**

(54) **PORTABLE ELECTRONIC FLARE**

- (71) Applicant: **Pi Variables, Inc.**, Tustin, CA (US)
(72) Inventors: **James R. Selevan**, Laguna Beach, CA (US); **Daniel Joseph Selevan**, Laguna Beach, CA (US)
(**) Term: **15 Years**
(21) Appl. No.: **29/613,191**
(22) Filed: **Aug. 8, 2017**

Related U.S. Application Data

- (63) Continuation-in-part of application No. 29/593,694, filed on Feb. 10, 2017.

(57)

CLAIM

The ornamental designs for portable electronic flare, as shown.

DESCRIPTION

FIG. 1 is a top, right perspective view of a portable electronic flare showing our new design; and, FIG. 2, is a bottom, left perspective view thereof. The broken lines depict unclaimed environmental subject matter.

1 Claim, 2 Drawing Sheets
